HOISTING DRUM SAFETY CONTROL

Floyd R. Spriggs, Beaver Dam, Ky.

Application January 10, 1950, Serial No. 137,683

4 Claims. (Cl. 254—187)

1

This invention relates to hoisting drum controls, and more particularly to a safety control effective to automatically stop the drum in the event of power failure or failure of the hoisting drum operating mechanism.

It is among the objects of the invention to provide a hoisting drum safety control for the hoisting drums of lifting and excavating machines, such as the large power shovels used in strip coal mining, which will automatically stop the drum in the event of power failure or failure of the drum operating mechanism to prevent dropping of the shovel or other device operated by the drum, which can be applied to an existing hoisting drum operating assembly with no material modification of the existing structure and does not interfere in any way with the normal operation of the hoisting drum, and which safety control includes a minimum number of parts of simple and durable construction, is economical to manufacture and easy to install, and is highly effective in preventing damage to the equipment to which it is applied.

Other objects and advantages will become apparent from a consideration of the following description and the appended claims in conjunction with the accompanying drawings wherein:

Figure 1 is an end elevation of a hoisting drum and operating mechanism therefor with safety control means illustrative of the invention operatively applied thereto, a portion of the drum operating mechanism being broken away to simplify the illustration;

Figure 2 is a top plan view of the drum and operating mechanism illustrated in Figure 1, portions being broken away and shown in cross section to better illustrate the construction of the device;

Figure 3 is a longitudinal cross section of a brake operating component of the assembly illustrated in Figure 1 and is taken substantially on the line 3—3 of Figure 1;

Figure 4 is a medial cross sectional view of the two electromagnetic valves illustrated in Figure 1;

Figure 5 is a cross sectional view on an enlarged scale on the line 5—5 of Figure 1;

Figure 6 is a cross section on the line 6—6 of Figure 5;

Figure 7 is a longitudinal cross section of a check valve taken on the line 7—7 of Figure 1; and

Figure 8 is a cross section of another check valve on the line 8—8 of Figure 1.

With continued reference to the drawings and

2

particularly to Figures 1 and 2, the numeral 10 designates a horizontally disposed hoisting drum shaft rotatably journaled in suitable bearings, not illustrated, carried by the fixed frame of the machine in which the hoisting drum is installed. A cable winding hoisting drum or spool 11 is journaled on the shaft and is externally threaded to provide cable receiving grooves 12 in which a cable is received as it is wound onto the drum. 10 The drum cable, not illustrated, is connected to a device to be raised and lowered by the winding drum, such as an elevator, a power shovel bucket or a crane boom.

A double drive gear 13 having peripheral gear teeth of herringbone formation is secured on the shaft 10 at one end of the drum 11 and this gear is driven by one or more power operated devices, such as electric motors having on their shafts spur gears meshing with the teeth of the gear 13.

20 An annular clutch element or drum is secured to the cable drum 11 at the end of the latter adjacent the gear 13 and is substantially coaxial with the cable drum and the shaft 10. A complementary clutch element or band 15 peripherally surrounds the drum carried brake element 14 and is secured at its ends to the gear 13 by the anchor pins 16 and 17 which extend through and are journaled in the spokes or web 18 of the gear. The anchor pin 16 is connected to one end 25 of the clutch band 15 by an adjustable connecting assembly 19 and the pin 17 is connected to the other end of the clutch band by an adjustable connecting assembly 20. The pin 17 has an eccentric cylinder 21 rotatably received in the connecting assembly 20 so that when the pin or shaft 17 is rotated in one direction the band 15 will be tightened around the drum 14 to provide a torque transmitting connection between the gear 13 and the drum 11 and when the pin 17 is 30 rotated in the opposite direction the clutch band will be released from the clutch drum to render the cable drum 11 freely rotatable relative to the gear 13 and shaft 10.

An arm 22 is secured at one end to the pin 17 35 at the side of the gear opposite the clutch elements 14 and 15 and this arm carries a crank 23 on its other end.

A flanged structure 24 is secured on the gear 13 between the hub 25 and the rim of the gear and includes a cylinder 26. A piston is reciprocable in the cylinder 26 and a piston rod 27 extends from the piston through the end of the cylinder adjacent the arm 22 and is connected to the crank 23 by a link 28. An inlet fitting 29 is secured to the structure 24 at the

end of the latter remote from the arm 22 and communicates with the interior of the cylinder 26. A conduit 30 extends from a bore in the shaft 10 to the inlet fitting 29 for supplying air under pressure to the cylinder. When compressed air is supplied to the cylinder the arm 22 is moved by the piston and piston rod 27 in a direction to contract the clutch band 15 thereby providing a torque transmitting connection between the gear and the cable drum 11 so that the cable drum will be rotated by the power operated driving means engaging the gear.

A source of compressed air 31, such as an air compressing pump, is provided and conduit means 32 and 33 connect this source of compressed air to the bore in the shaft 10 and a manually controlled solenoid valve 34 is connected into the conduit means 32 and is so arranged, as particularly illustrated in Figure 4, that when the power to the solenoid is cut off by opening a suitable switch or by failure of power to the solenoid the valve is positioned to connect the compressed air source 31 to the cylinder 26 to engage the clutch and when the solenoid circuit is completed by closing the manually operated switch the valve is positioned to cut off the supply of air to the cylinder 26 and vent the cylinder so that the clutch will be released. When the cylinder is vented the arm 22 is moved in a clutch releasing direction by a tension spring 35 connected at one end to the arm 22 and at its opposite end to a lug formation 36 on the flanged structure 24.

A brake element or drum 37 is secured to the cable drum 11 at the end of the drum opposite the clutch element 14 and is disposed coaxially of the drum. A complementary brake element or band 38 surrounds the brake drum 37 and a brake actuating lever 39 is pivotally mounted on a fixed support 40 and pivotally connected at one end to one end of the brake band 38, as indicated at 41. The other end of the brake band 38 is connected to the pin 42 which connects the lever 39 to the fixed support 40 by a clip or link 43. A brake cylinder 44 is mounted on a fixed support and includes a piston 45. A piston rod 46 extends from the piston through one end of the brake cylinder and is secured by a link 47 to the end of the lever 39 opposite the end of the lever connected to the brake band. A spring abutment 48 is secured on the piston rod 46 within the cylinder 44 and a heavy compression spring 49 surrounds the piston rod between the abutment 48 and the end of the cylinder adjacent the lever 39 and is effective to resiliently move the piston rod 46 in a direction to contract the brake band 38 upon the brake drum 37 and apply the brake.

A conduit 50 extends from a T-connection 51 with the conduit 32 to the end of the brake cylinder 44 remote from the lever 39 for the application of fluid under pressure into the space between the piston 45 and the end of the brake cylinder to which the conduit 50 is connected to move the piston 45 in a direction to release the brake.

A solenoid valve 52 is connected into the conduit 50 and is controlled by a manually operated switch, not illustrated. This valve 52 is so arranged that when power is applied to its solenoid it admits fluid under pressure to the cylinder 44 to release the brake and when its solenoid is de-energized, either by opening the associated switch or by power failure, it closes off

the side of the conduit 50 adjacent the T-fitting 51 and thence the brake cylinder so that the spring 49 is rendered effective to apply the brake.

With this arrangement the solenoid valves 34 and 52 can be manually controlled to release the brake and engage the clutch, to release the clutch and simultaneously engage the brake or to engage both the clutch and the brake in the event of power failure to the machine.

The above described construction is all old and well known except for the particular arrangement of the solenoid valves 34 and 52 and the conduits 32, 33 and 50 which arrangement constitutes a part of the present invention for providing an automatic safety control for the hoisting drum. The invention further embodies a trip valve, generally indicated at 53, mounted on the gear 13 and connected by a conduit 54 and T-fitting 55 to the conduit 30, a check valve 56 interposed between the T-fitting 55 and the inlet fitting 29 for the cylinder 26 and a check valve 57 interposed in the conduit 50 which leads from the solenoid valve 52 to the brake cylinder 44.

The trip valve 53 comprises a flanged body 58 which includes a hollow valve body 59 and is mounted on the gear 13 adjacent the end of the piston rod 27 projecting from the cylinder 26 of the body 24. The conduit 54 is connected into one end of the hollow valve body 59 and the other end of the valve body is open and internally screw threaded. A nut 60 having a bore therethrough is threaded into the open end of the valve body and a poppet valve 61 has its stem 62 slidably mounted in the nut 60 and its head 63 co-operating with a beveled valve seat 64 formed in the valve body. A vent opening 65 is provided in the valve body at the side of the seat 64 opposite the end of the body to which the conduit 54 is connected.

An arm 66 projects from the valve body 59 at the end thereof receiving the nut 60 in a direction away from the end of the valve body receiving the conduit 54 and an apertured lug 67 is provided on the opposite side of the valve body. A lever 68 is pivotally connected at one end to the lug 67 and extends in a direction away from the end of the valve body receiving the conduit 54 and intermediate its length this lever is provided with an opening 69 having a detent formation 70 therein. A bar 71 is pivotally connected at one end to the arm 66 at the end of the arm 66 opposite that connected to the valve body 59 and this bar extends through the opening 69 in the arm or lever 68 and has a shallow notch in which the detent 70 is seated. The bar 71 overlies the adjacent end of the valve stem 62 and is provided with a screw threaded aperture which is in longitudinal alignment with the valve stem. An adjusting screw 72 is threaded through the aperture in the bar 71 and bears at one end on the adjacent end of the valve stem. The lever 68 is provided at its end opposite that pivotally connected to the valve body with a screw threaded aperture and a stud bolt 73 is threaded through this aperture and secured in adjusted position by a lock nut 74.

A projection 75 is provided on the end of the piston rod 27 connected to the link 28 and the trip valve 53 is so mounted on the gear that one end of the bolt 73 is in alignment with the projection 75 in the direction of movement of the piston rod and is normally spaced from this projection.

The distance between the projection 75 and adjacent end of the bolt 73 is such that the piston rod 27 can move to engage the clutch without contacting the bolt but, if the arm 22, the clutch band 15 or some other part of the clutch operating mechanism breaks, the piston rod will move an additional distance and will contact the bolt 73 and move the detent 70 beyond the adjacent end of the bar 11. This release of the bar 11 will release the valve 61 from its seat 64 so that the conduit 54 will be directly connected with the vent opening 65 in the valve body. This will immediately vent the conduits 30, 33 and 50 and free the brake spring 49 to engage the brake and hold the cable drum against movement thereby precluding dropping of a shovel bucket, elevator or other device operated by the cable drum.

When the two solenoid valves 34 and 52 are in position as illustrated in Figure 4 with the electric power on but with the solenoid 76 of the valve 34 de-energized by the opening of a manually operated switch connected into its energizing circuit, the fluid under pressure, such as compressed air, flows from the compressor 31 to the valve 34 and through this valve and the conduit 32 to the T-fitting 51 and the conduits 33 and 50, the solenoid 77 of the valve 52 being energized. This supplies air under pressure to the clutch operating cylinder 26 and the brake cylinder 44 simultaneously, engaging the clutch and releasing the brake. Under these conditions the drum 11 will be rotated by the gear 13 for lifting the device operated by the drum. When it is desired to stop the drum the solenoid 76 is energized and the solenoid 77 is simultaneously de-energized whereupon the valve 34 will vent the conduit 32 and the conduits 33 and 30, releasing the clutch and the valve 52 will vent the conduit 50 freeing the spring 49 to engage the brake.

In the event of power failure to the machine both solenoids 76 and 77 will be de-energized and, if the valves were in drum rotating position, as illustrated in Figure 4, at the time of power failure the valve 34 will remain in the same position maintaining a supply of compressed air to the clutch cylinder to keep the clutch engaged while the valve 52 will move to its venting position to also engage the brake, the clutch and brake together holding the drum against rotation during the time the power is off.

Connecting the conduit 33 leading to the clutch operating cylinder between the two valves 34 and 52 is an improvement of the present invention and, with this arrangement, if the trip valve 53 is tripped to vent the brake cylinder and apply the brake upon failure of some part of the clutch operating mechanism, the clutch valve can be immediately closed by energizing its solenoid 76 and this will cut off the supply of compressed air from the compressed air source 31 so that the compressed air in the reservoir tank will not be exhausted and the supply of compressed air to the broken clutch operating mechanism will be discontinued.

The check valve 56 is fully open when air is flowing through the conduit 30 to the inlet fitting 29 of the clutch operating mechanism so that flow of air in this direction is not substantially obstructed but provides a restriction to the flow of air in the opposite direction. The check valve 57 provides for a substantially unrestricted flow of air from the brake cylinder 44 through the conduit 50 but restricts the flow of air through the conduit 50 to the brake cylinder.

With this arrangement, when the valves 34

and 52 are operated to release the clutch and engage the brake, the brake spring 49 will be immediately freed to engage the brake but the disengagement of the clutch will be slightly retarded so that the clutch will be held in engagement until the brake is fully engaged thus precluding any free period for drum rotation between release of the clutch and engagement of the brake. On the other hand, when the valves 34 and 52 are operated to release the brake and engage the clutch the free flow of air to the clutch operating cylinder will quickly engage the clutch but the restricted flow of air to the brake cylinder will slightly retard the release of the brake so that the clutch will be fully engaged before the brake is released.

If the supply of compressed air or other operating fluid under pressure should suddenly fail by breakage of any one of the conduits or failure 20 of the compressor while the drum is being driven, the valve 56 would retard the release of the clutch until the brake was fully engaged by the spring 49 to avoid the possibility of dropping the shovel or elevator under these conditions.

The two check valves 56 and 57 may be of any desired construction but, as illustrated, the valve 56 comprises a hollow valve body 80 having a tapered, annular valve seat 81 formed intermediate the length thereof and having one end 30 internally screw threaded to receive the corresponding end of the conduit 30. At its opposite end the body 80 is recessed and externally screw threaded and a second hollow valve body 82 has an internally screw threaded counterbored end 35 threaded onto the recessed end of the body 80. At its other end the body 22 is internally screw threaded to receive the corresponding end of the conduit 30 and an apertured guide 83 within the body 82 slidably supports the stem 84 of 40 a poppet valve 85 having a head 86 engageable with the valve seat 81 to close the valve. A light spring 87 surrounds the valve stem between the guide 83 and the head 86 and urges the valve head into seating engagement with the seat 81. A bleed opening 88 extends through the valve head to permit the restricted passage of air through the check valve when the valve is closed.

The valve 57 is similar in construction comprising two hollow valve bodies 90 and 91 similar to the bodies 80 and 82 of the valve 56, a poppet type valve 92 engageable with a seat in the body 90 and having a bleed opening 93 through its head and a spring 94 resiliently urging the valve head into seating engagement with the valve seat in the body 90.

The present safety control thus comprises three changes or additions to the existing drum control structure including the rearrangement 60 of the air supply conduit to the clutch operating mechanism in relation to the solenoid operated valves 34 and 52, the provision of the check valves 56 and 57 in the conduits supplying compressed air to the clutch operating mechanism and to the brake operating mechanism and the trip valve 53 operated by the clutch operating mechanism in the event of breakage of any of the clutch operating parts.

The invention may be embodied in other specific forms without departing from the spirit or essential characteristics thereof. The present embodiment is, therefore, to be considered in all respects as illustrative and not restrictive, the scope of the invention being indicated by the appended claims rather than by the fore-

going description, and all changes which come within the meaning and range of equivalency of the claims are, therefore, intended to be embraced therein.

What is claimed is:

1. In combination with a cable drum and operating assembly therefor including a shaft, a drum on said shaft, a power driven gear on said shaft at one end of said drum, a clutch element carried by said drum, a clutch element carried by said gear and engageable with the drum carried clutch element to provide a torque transmitting connection between said gear and said drum, a fluid pressure operated expandable chamber device carried by said gear and connected to the gear carried clutch element to engage the gear carried element with the drum carried element, a brake element carried by said drum, a complementary brake element fixed relative to the drum carried brake element, a spring connected to the relatively fixed brake element resiliently urging the latter into braking engagement with said drum carried brake element, a fluid operated expandable chamber device connected to said relatively fixed brake element for releasing the latter from said drum carried brake element against the force of said spring, a source of fluid under pressure, conduit means connecting said source of fluid under pressure to said expandable chamber devices for simultaneously engaging said clutch elements and releasing said brake elements by the application of fluid under pressure to both of said expandable chamber devices, manually controlled valve means in said conduit means for cutting off the supply of fluid under pressure to said expandable chamber devices and venting said devices to simultaneously release said clutch elements and engage said brake elements, a trip valve mounted on said gear adjacent said gear carried expandable chamber device and connected into said conduit means to vent said expandable chamber device connected to said relatively fixed brake element when said trip valve is opened to thereby release said spring to engage said brake elements, said trip valve being opened by the gear carried expandable chamber device when the latter moves beyond its normal clutch element engaging position incident to failure of said clutch elements to drivingly engage.

2. In combination with a cable drum and operating assembly therefor including a shaft, a drum on said shaft, a power driven gear on said shaft at one end of said drum, a clutch element carried by said drum, a clutch element carried by said gear and engageable with the drum carried element to provide a torque transmitting connection between said gear and said drum, a fluid pressure operated expandable chamber device carried by said gear and connected to the gear carried clutch element to engage the gear carried element with the drum carried element, a brake element carried by said drum, a complementary brake element fixed relative to said drum carried brake element, a spring connected to the relatively fixed brake element resiliently urging the latter into braking engagement with said drum carried brake element, a fluid operated expandable chamber device connected to said relatively fixed brake element for releasing the latter from said drum carried brake element against the force of said spring, a source of fluid under pressure, a first manually controlled valve connected to said source of fluid under

pressure, a first conduit connecting said valve to the expandable chamber device carried by said gear, said first manually controlled valve having one operative position in which it connects said source of pressure with the gear carried expandable chamber device and another operative position in which it cuts off said source of air under pressure and vents said gear carried expandable chamber device, a second manually controlled valve, a second conduit connecting said second manually controlled valve to said first mentioned conduit, and a third conduit connecting said second manually controlled valve to said expandable chamber device connected to said relatively fixed brake element, said second manually controlled valve having two operative positions in one of which it connects said first mentioned conduit to said expandable chamber device connected to said relatively fixed brake element and in the other of which it closes off said second conduit and vents said expandable chamber device connected to said relatively fixed brake element.

3. In combination with a cable drum and operating assembly therefor including a shaft, a drum on said shaft, a power driven gear on said shaft at one end of said drum, a clutch element carried by said drum, a clutch element carried by said gear and engageable with the drum carried element to provide a torque transmitting connection between said gear and said drum, a fluid pressure operated expandable chamber device carried by said gear and connected to the gear carried clutch element to engage the gear carried element with the drum carried element, a brake element carried by said drum, a complementary brake element fixed relative to said drum carried brake element, a spring connected to the relatively fixed brake element resiliently urging the latter into braking engagement with said drum carried brake element, a fluid operated expandable chamber device connected to said relatively fixed brake element for releasing the latter from said drum carried brake element against the force of said spring, a source of fluid under pressure, a first manually controlled valve connected to said source of fluid under pressure, a first conduit connecting said valve to the expandable chamber device carried by said gear, said first manually controlled valve having one operative position in which it connects said source of pressure with the gear carried expandable chamber device and another operative position in which it cuts off said source of fluid under pressure and vents said gear carried expandable chamber device, a second manually controlled valve, a second conduit connecting said second manually controlled valve to said first mentioned conduit, a third conduit connecting said second manually controlled valve to said expandable chamber device connected to said relatively fixed brake element, said second manually controlled valve having two operative positions in one of which it connects said first mentioned conduit to said expandable chamber device connected to said relatively fixed brake element and in the other of which it closes off said second conduit and vents said expandable chamber device connected to said relatively fixed brake element, a check valve in said first mentioned conduit adjacent said gear carried expandable chamber device arranged to provide a substantially unrestricted flow of fluid to the associated expandable chamber device and a restricted flow of fluid away from the associated expandable chamber device, and a second

check valve in said third conduit adjacent said expansible chamber device connected to said relatively fixed brake element and arranged to provide a substantially unrestricted flow of fluid away from the associated expansible chamber device and a restricted flow of fluid to the associated expansible chamber device.

4. In combination with a cable drum and operating assembly therefor including a shaft, a drum on said shaft, a power driven gear on said shaft at one end of said drum, a clutch element carried by said drum, a complementary clutch element carried by said gear and engageable with the drum carried clutch element to provide a torque transmitting connection between said gear and said drum, a first fluid pressure operated expansible chamber device carried by said gear and connected to the gear carried clutch element to engage the gear carried clutch element with the drum carried element, a brake element carried by said drum, a complementary brake element fixed relative to the drum carried brake element, a spring connected to the fixed brake element resiliently urging the latter into braking engagement with said drum carried brake element, a second fluid pressure operated expansible chamber device connected to said fixed brake element for releasing the latter from said drum carried brake element against the force of said spring, a source of fluid under pressure, a first conduit connecting said source of fluid under pressure to said second expansible chamber device, two manually controlled valves connected into said first conduit at spaced apart locations therealong and each having one operative position in which it continues said conduit and another operative position in which it interrupts said conduit and vents the portion of the conduit at the side of

5 10 15 20 25 30

the valve remote from said source of fluid under pressure, a first check valve in said first conduit between said second expansible chamber device and the manually controlled valve adjacent thereto, said first check valve being operative to provide a substantially unrestricted flow of fluid away from said second expansible chamber device and a restricted flow of fluid to the latter, a second conduit connecting said first conduit between said manually controlled valves to said first expansible chamber device, a trip valve mounted on said gear adjacent said gear carried expansible chamber device, a third conduit connecting said second conduit to said trip valve, said trip valve being operated by movement of said first expansible chamber device beyond its normal clutch element engaging position upon failure of said clutch elements to engage to vent said second and third conduits and said first expansible chamber device, and a second check valve in said second conduit between said third conduit and said first expansible chamber device and operative to provide a substantially unrestricted flow of fluid to said first expansible chamber device and a restricted flow of fluid away from said first expansible chamber device.
